UNITED STATES PATENT OFFICE.

MORTIMER C. COGSWELL, OF BROOKLYN, NEW YORK.

GRINDING-MILL.

SPECIFICATION forming part of Letters Patent No. 367,189, dated July 26, 1887.

Application filed August 11, 1886. Serial No. 210,617. (No model.)

To all whom it may concern:

Be it known that I, MORTIMER C. COGSWELL, of Brooklyn, county of Kings, State of New York, and a citizen of the United States, 5 have invented certain new and useful Improvements in Grinding-Mills, of which the following is a full, clear, and exact description, reference being had to the accompanying drawings, forming part of this specification.

10 My present invention relates to improvements upon the grinding-mill for which Letters Patent No. 324,363 were granted to me August 18, 1885; and my invention consists in the combination, in a grinding-mill, with the 15 shaft carrying a balanced disk provided with concentric series of bolt-holes, of similar grinding-plates of uniform weight, provided with similarly-located bolt-holes registering with the bolt-holes in the disk and formed with recesses containing soft metal, and screw-bolts for securing said plates to said disk, whereby the said plates are made interchangeable as to both form and weight, and the balance of the 20 grinding-disk preserved.

25 Figure 1 is a side elevation of the mill, partly in central longitudinal section, to which my invention relates and containing the elements of my present invention. Fig. 2 is a face view of one of the revoluble independently- 30 balanced disks, showing the independently-balanced segmental grinding-plates mounted in a set upon the disk in conformity with my invention. Fig. 3 is a rear face view of one of the segmental grinding-plates. Fig. 4 is a 35 cross-section of said plate on line xx , Fig. 3; and Fig. 5 is a similar view of the same, showing the plate balanced in conformity with my invention.

A is the frame on which are mounted the 40 working parts.

B and B' are two shafts mounted to revolve in bearings in the frame.

F and F' are pulleys on the respective shafts to drive the same.

45 C and C' are two disks secured, respectively, to the inner or opposed ends of the shafts B and B' , so that the inner faces of the disks are opposed to one another in parallel planes with a space between them.

50 D is a curb inclosing the disks, and is provided with a spout, a , leading to openings cen-

tral of the curb and disk C' for the introduction of the material to be ground.

E is a hopper leading to the spout a , through which the material to be ground in the mill 55 may be conveniently fed. An opening, b , in the curb is provided, through which the ground material may be withdrawn from the mill.

So far as above described the mill will be 60 recognized as substantially similar to that described and shown in my patent hereinbefore referred to.

In carrying out my present invention the disks C and C' are themselves each balanced independently of the parts thereafter mounted 65 upon them, and before such parts are mounted upon them, as hereinafter described. These disks are separately balanced on their respective shafts—that is to say, the weight of the metal is distributed equally around the axial 70 center of the shaft, so that in rotation all parts will develop centrifugal force equally. This may be effected by any of the well-known methods employed for such purpose.

ccc , &c., are plates, preferably of hard metal, 75 such as chilled cast-iron, each in the form of a section of a disk and all of the same or equal size or area, so that when assembled, as shown in the drawings, they will constitute a disk or annulus of about the same, or not greater, 80 external diameter than that of the disks C or C'. Each of these plates is preferably provided on the grinding-face with radial ribs, as shown, the opposite face being preferably a plane for contact with the face of the disk. 85 These sectional plates c are all individually balanced, so that each is of equal weight with every other. This balancing of the plates may be accomplished and secured by mounting one of the plates upon a shaft upon one side thereof— 90 as, for example, by mounting it flatwise upon a suitable disk or other equivalent holder on the shaft and mounting another plate on the diametrically-opposite side of the shaft on said disk or holder at the same distance from the 95 axial center as the first, and then balancing said plates so that they will develop equal centrifugal force when revolved as thus held on the shaft. When the two plates are thus balanced, one of them is removed, and all the 100 others are successively placed in the position on the shaft thus vacated, and brought to equal

weight and balanced, as in the first instance described. The plates will all be thus individually and interchangeably balanced. To enable this described balancing of the plates to be economically, quickly, and effectively done, I cast or otherwise form a recess—preferably a dovetail recess—in the rearward or plane face of each plate, as shown at *d*, and put into this recess soft metal, such as lead, preferably by melting and running it in, and which may be added to or taken from, as may be required. In this way the plates may all be brought to the same or equal weights, one with another, and thus be balanced on the shaft.

With the described balanced disks *C* and *C'* I combine the said grinding-plates *c*, which have been uniformly balanced, as has been described, by such means and in such manner that the plates *c* on the disks *C* and *C'*, respectively, are interchangeable one with another or with others similarly balanced. To accomplish this, I provide the plates with the concentric series of bolt-holes *c'*, the bolt-holes in each plate being coincident in position therein with the bolt-holes in every other plate; and I provide the said disks with bolt-holes located therein similarly to and registering with the series of those in the plates, as shown. The screw-bolts *c''* pass through these bolt-holes thus constituted and arranged when the plates are assembled on the disks, as shown in the drawings, and the plates are thus held to the disks, while at the same time the plates are interchangeable on the disks as to both form and weight and the balance of the disks preserved.

In the operation of these mills the grinding devices are rotated in opposite directions, respectively, at high speed. In a mill of ordinary size, in which the disks are about eighteen inches in diameter, the speed is usually eighteen hundred to two thousand revolutions per minute, the grinding being effected by concussion and attrition of the particles of the material to be ground by being struck and thrown violently back and forth by and between the ribbed faces of the grinding-plates. The necessity of having the oppositely revolving grinding devices accurately balanced, and this balance maintained, is thus apparent.

The object of my invention is to secure this accurate balance of the revolute grinding devices, and at the same time to provide for the ready and convenient restoration of this balance when the same may be disturbed and the effectiveness of the mill consequently interfered with by the wear attendant upon the ribbed grinding-surfaces in their action. It is evident that by means of the devices I have

described, constructed, and combined, as specified, in case and when the wear upon the ribbed surface of any of the segmental plates *c* causes the segment to be thrown out of balance, the plate may be removed from the disk and either rebalanced and replaced; or a new plate of uniform balance with all the other plates, as herein set forth, may be substituted for the old one; or, when the wear is sufficient to destroy the usefulness of the entire set of plates, the set may be removed by the user of the mill and a new set of similar uniformly-balanced segmental plates may be mounted upon the disk, and the operation of the mill at once proceeded with. The opposed faces of the disks *C* and *C'* not being subject to wear in the operation of the mill, their described original balance is at all times preserved, and the plates are removable from and interchangeable upon the disks, and the balance of the combined disks and plates is at all times maintained.

I am aware that individually-balanced disks are not new in mills, and I do not claim such disks herein, broadly. Nor do I claim, broadly, herein segmental grinding-plates made of uniform size or area, as such plates have been heretofore made.

What I claim as my invention, and desire to secure by Letters Patent, is—

1. In a grinding-mill, the combination, with the shaft *B* and the balanced disk *C*, provided with concentric series of bolt-holes, of the similar grinding-plates of uniform weight, provided with similarly-located bolt-holes registering with the bolt-holes in the disk and formed with recesses *d*, containing soft metal, and the screw-bolts *c''*, for securing said plates to said disks, whereby the said plates are rendered interchangeable as to both form and weight and the balance of the grinding-disk preserved, as set forth.

2. In a grinding-mill, the combination of the shafts *B* and *B'*, the independently-balanced similar disks *C* and *C'*, each provided with concentric series of bolt-holes, the similar grinding-plates of uniform weight, provided with similarly-located bolt-holes registering with the bolt-holes in the disks and formed with recesses *d*, containing soft metal, and the screw-bolts *c''*, for securing said plates to said disks, whereby the said plates are rendered interchangeable in both form and weight and capable of being applied to either disk without disturbing the running balance of the mill, as set forth.

MORTIMER C. COGSWELL.
